UNITED STATES PATENT OFFICE.

KARL HAMM, OF HARTFORD, CONNECTICUT.

STEAM BOILER.

Application filed May 14, 1926. Serial No. 109,055.

This invention relates to steam boilers, and has for its primary object to provide a steam boiler having a maximum heat radiating surface and which may be economically operated with the use of fuel oil or gas to quickly convert the water contained in the boiler into steam at the requisite pressure.

In one practical embodiment of the invention, I provide a drum axially positioned within the boiler shell and internally divided into a plurality of separate chambers, into one of which the flames and gas are initially admitted from the oil burner mounted in one end of said drum. A plurality of conducting tubes for the gas are in communication at their ends with adjacent chambers of the drum and extend downwardly into the water contained in the boiler so that in the passage of the hot gases successively through these tubes or conduits successively through the several chambers, the heat will be radiated from the walls of said tubes as well as from the wall of the drum. In addition, I preferably provide an elongated pipe coil arranged in the bottom of the boiler shell and connected at one of its ends to one end of the drum and into which the gases are finally emitted, said pipe coil discharging into a suitable outlet flue. Thus, all of the available heat contained in the gas will be practically abstracted therefrom and utilized in the conversion of the water into steam.

It is another object of the invention to provide improved means for directing a multiplicity of water jets in spray form upon the upper part of the heated drum so that the water spray will be instantly converted into steam upon contact with the heated wall of said drum, thereby expediting the increase of steam pressure within the boiler to the desired point.

It is also a further general object of the invention to provide a steam boiler having the above novel features which is relatively simple in its construction, efficient in its practical operation and which may be produced at relatively small cost.

With the above and other objects in view, the invention consists in the improved steam boiler, and in the form, construction and relative arrangement of the various parts thereof as will be hereinafter more fully described, illustrated in the accompanying

drawings, and subsequently incorporated in the subjoined claims.

In the drawings, wherein I have illustrated one simple and practical embodiment of the invention and in which similar reference characters designate corresponding parts throughout the several views,

Figure 1 is a side elevation of a steam boiler embodying my present improvements;

Fig. 2 is a transverse sectional view taken substantially on the line 2—2 of Fig. 1, and

Fig. 3 is an enlarged longitudinal sectional view taken substantially on the line 3—3 of Fig. 2.

Referring in detail to the drawings, the boiler shell indicated at 5 is preferably of cylindrical form and may be of any desired size and capacity, the opposite ends of said shell being closed by the heads 6 and 7, respectively.

The boiler head 6 is centrally provided with a reduced axial extension 8 in the form of a cylindrical wall or tube, to one end wall of which, one end of the elongated drum 9 is permanently fixed. This drum extends axially within the boiler shell 5 to a point adjacent the opposite end thereof and is provided with a plurality of equidistantly spaced internal partition walls 10. These partition walls provide a flame and gas receiving chamber 11 at the forward end of said drum, a plurality of intermediate chambers 12 constituting gas passages of substantially equal area and a gas outlet chamber 13 at the rear end of said drum.

In the forward end of the drum 9 an oil burner of any suitable type indicated at 14 is suitably mounted. The flame and gases initially discharged into the chamber 11 are successively conducted to and through the chambers 12 and finally into chamber 13 by a plurality of substantially U-shaped tubes or conduits 15 disposed in pendent relation to the drum 9 and having their open ends in communication with the adjacent chambers of the drum.

In addition to the tubes or conduits 15 and below the same, an elongated pipe coil 16 is arranged in the boiler and extends substantially the full length thereof. One end 17 of this pipe coil is connected with the outlet chamber 13 while the other end 18 of said coil extends through the boiler head 7 and opens into a suitable discharge flue 19.

The boiler is filled with water through a suitable water supply connection indicated at 20 until the pendent tubes 15 are entirely submerged, and the water level is substantially on a line with the axis of the drum 9. The flame and the products of combustion entering chamber 11 from the burner 14 pass successively through the depending tubes or conduits 15 and chambers 12, such 10 travel or passage of the gases through these chambers being aided by the induced suction from the outlet flue 19. The cylindrical wall of the drum 9 thus becomes very highly heated, such heat being transmitted into the 15 surrounding water so that the latter is converted into steam. Any remaining heat units contained in the gas is abstracted therefrom in the passage of the gas through the elongated pipe coil 16. In this manner, I 20 obtain a maximum utilization of the heat contained in the burner flame and gases before the gases are finally discharged into the outlet flue 19.

For the purpose of expediting the generation of the desired steam pressure in the starting of the boiler operation, I provide the upper portion of said boiler with a plurality of water spray nozzles indicated at 21 which are connected with a source of water supply 25 by the pipes 22. Thus at spaced points longitudinally of the boiler, a plurality of spray jets of water in finely divided form are directed radially upon the wall of the drum 9. This drum wall being highly heated, the 30 globules of water upon impact therewith, will be immediately converted into steam, thereby supplementing the volume of steam produced from the water in the lower part of the boiler and rapidly increasing the 35 steam pressure therein.

Preferably, the boiler shell at its upper 40 side and centrally thereof is provided with a steam collecting dome 23 equipped with the usual safety valve indicated at 24 and the outlet pipe connection 25 having a suitable 45 control valve 26 therein and through which the steam may be drawn off and utilized for various purposes.

From the foregoing description considered 50 in connection with the accompanying drawings, the construction and manner of operation of my improved steam boiler will be fully understood. The invention is well adapted for the purpose of household heating by means of oil and similar liquid fuel, and is capable of very economical operation. Of course, the oil burner may be equipped 55 with the usual automatic control devices whereby the supply of oil is regulated in accordance with the requirements to maintain a predetermined steam temperature and pressure.

While I have herein shown and described 60 one practical example of my present improvements, it will nevertheless, be under-

stood that in its several novel features, the invention might be structurally exemplified in numerous other alternative embodiments, and I therefore, reserve the privilege of resorting to all such legitimate changes in the 70 form, construction and relative arrangement of the several parts as may be fairly incorporated within the spirit and scope of the appended claims.

I claim:

1. In a steam boiler, a boiler shell, a drum axially positioned therein and provided with a plurality of chambers, a plurality of gas conducting tubes depending from said drum and connecting said chambers with each other, said tubes and lower part of the drum adapted to be submerged in water contained in the boiler, means for supplying a fluid heating medium to one end chamber of said drum, an elongated pipe coil arranged in the lower side of the boiler beneath said conduits and having one end thereof connected with the other end chamber of said drum and the other end of said coil discharging the gases externally of the boiler. 90

2. In a steam boiler, a boiler shell, a drum extending axially within said shell, said drum at one of its ends being rigidly supported upon one end of the boiler shell, a liquid fuel burner mounted in the latter 95 end of said drum, a plurality of spaced internal partitions dividing said drum into a plurality of chambers, conduits connecting the adjacent chambers with each other and conducting the burner gases successively through said chambers, and a pipe coil connected at one of its ends with the other end chamber of said drum and through which the gases are discharged externally 100 of the boiler, said pipe coil, the conduits and the lower part of said drum adapted to be submerged in water contained in the boiler shell.

3. In a steam boiler, a boiler shell, a drum axially positioned therein and provided with a plurality of chambers, a plurality of gas conducting tubes depending from said drum and connecting said chambers with each other, said tubes and lower part of the drum adapted to be submerged in water contained in the boiler, means for supplying a fluid heating medium to one end chamber of said drum, means for discharging the gases and products of combustion from the same at the opposite end of said drum, and a plurality of water spray nozzles mounted in the upper side of the boiler shell for directing a series of spray jets of water upon the upper part of the drum wall. 115

4. In a steam boiler, a boiler shell, a drum axially positioned therein and provided with a plurality of chambers, a plurality of gas conducting tubes depending from said drum and connecting said chambers with each other, said tubes and lower part of the drum 125 130

- adapted to be submerged in water contained in the boiler, means for supplying a fluid heating medium to one end chamber of said drum, an elongated pipe coil arranged in the 5 lower side of the boiler beneath said conduits and having one end thereof connected with the other end chamber of said drum, the other end of said coil discharging the 10 gases externally of the boiler, and a plurality of water spray nozzles mounted in the upper side of the boiler shell for directing a series of spray jets of water upon the upper part of the drum wall.
5. In a steam boiler, a boiler shell, a plurality of chambers serially arranged in the shell away from the walls thereof, a plurality of gas conducting tubes depending from said chambers and connecting each succeeding chamber, means for supplying a 15 fluid heating medium to a burner located in one chamber, means for discharging the gases and products of combustion from the chamber at the opposite end of the shell, and means for spraying water upon the upper 20 side of said chambers.
6. In a steam boiler, a boiler shell, a plurality of chambers serially arranged in the shell in horizontal alignment and spaced from the wall thereof, a plurality of gas 25 conducting tubes depending from said chambers and connecting the succeeding chamber and submerged in the water contained in the boiler, means for supplying a fluid heating medium to a burner located in one 30
- end chamber, and means for discharging the 35 gas and products of combustion from the chamber at the opposite end of the shell, means for spraying water upon the upper ends of the chambers.
7. In a steam boiler, a boiler shell, a series 40 of chambers arranged axially within the shell and partly submerged in the water thereof, a plurality of gas conducting tubes depending from said chambers and connecting the succeeding chambers and submerged 45 within the water contained in the shell, means for supplying a fluid heating medium to a burner located in one end chamber, means for discharging the gas and products 50 of combustion from the chambers at the opposite end of the shell, and a coil connected to the discharge and arranged below the depending tubes and extending out through the shell.
8. In a steam boiler, a boiler shell, a plurality of chambers arranged serially within said shell in axial alignment, depending tubes connecting said chambers, a fluid supply heating medium for one end chamber, means for discharging the gases and products 55 of combustion from the other end chamber, and a coil connected to the discharge and arranged in the shell below the depending tubes.

In testimony that I claim the foregoing as 60 my invention, I have signed my name hereto.

KARL HAMM.
